United States Patent Office

Des. 192,247
Patented Feb. 20, 1962

192,247

TELEPHONE CALL INDICATOR

Theodore T. Michals, 350 Fairbank Road, Riverside, Ill.

Filed May 12, 1961, Ser. No. 65,149

Term of patent 3½ years

(Cl. D26—14)

FIG. 1

FIG. 2

FIGURE 1 is a perspective view of the front and one side of a telephone call indicator, showing my new design.

FIG. 2 is a perspective view of the rear and side opposite that shown in FIG. 1.

I claim:

The ornamental design for a telephone call indicator, as shown.
